UNITED STATES PATENT OFFICE.

HORATIO CAMERON, OF BOSTON, ASSIGNOR OF ONE-HALF TO EDWIN L. EDES, OF PLYMOUTH, MASSACHUSETTS.

WIRE-NAIL MACHINE.

SPECIFICATION forming part of Letters Patent No. 390,648, dated October 9, 1888.

Application filed November 28, 1887. Serial No. 256,303. (No model.)

To all whom it may concern.

Be it known that I, HORATIO CAMERON, a citizen of the United States, residing at Boston, in the county of Suffolk and State of Massachusetts, have invented a new and useful Improvement in Attachments for Cutting Wire Nails and Wire Tacks, as applied to a Blanchard tack and nail machine, of which the following is a specification.

10 The object of my invention is to produce an attachment for a Blanchard tack and nail machine, whereby I am enabled to make wire nails or tacks with the said machine.

The invention consists in the peculiar construction and arrangement of the pointing, feeding, and cutting mechanism, as hereininafter fully set forth, and pointed out in the claims.

Referring to the accompanying drawings, Figure 1 represents a front view of a Blanchard tack and nail machine with my invention applied thereto. Fig. 2 is a rear view of the feeding-bar; Fig. 3, a side view of the same. Fig. 4 shows, respectively, a section through *x x* of Fig. 2 and through *y y*. Fig. 5 shows a 25 rear view of a modification of the feed-bar. Fig. 6 is a side view of same. Fig. 7 is a detail view showing the wire pointed and ready to be cut off. Fig. 8 is a plan or top view of same. Fig. 9 is a view showing the wire cut off and carried down to the heading mechanism. Fig. 10 is a plan or top view of same.

A represents the frame of a Blanchard tack or nail machine; B, the shaft upon which are mounted the gripping-lever C and cams D D², 35 for operating the cutting-jaws E E². Upon one end of the shaft B is mounted the driving wheel or pulley D³, and upon the other end is mounted an eccentric-disk, K, for operating the pitman J, that communicates motion to 40 the heading-lever H, to which the heading-tool I is secured.

F is the bed-piece; C², the fixed gripping-jaw, which, together with the movable gripping-jaw C, holds the nail while being headed, 45 and L is the bearer for carrying the nail down to the same.

All of the above parts are old and of well-known construction. Therefore it is not necessary to particularly describe their construction and operation.

In the Blanchard machine to each of the cutting-jaws E E² a knife is secured parallel with the front of the machine. These I dispense with, and in their place arrange the following mechanism: To the inner side of the cutting-jaw E², I secure a knife, M, so that the knife is at right angles to the front of the machine and next to the jaw E², and to the said jaw E², I also secure a die, N, and to the bed-piece F, I secure a corresponding die, P. These dies N and P are for pointing the wire, as will be hereinafter fully explained. To the other jaw, E, I secure a stay, Q, for steadyng the knife M while cutting the wire.

To one side of the frame of the machine I 65 secure a plate, R, provided with a slot, r. (See Fig. 1.) This plate is for carrying the feed-bar S, which is connected thereto by a stud, T. This stud consists of a central portion, t, of slightly larger diameter than the ends t' t'', 70 which are both screw-threaded. (See Fig. 4.) Upon the portion t' is placed a washer, u, that bears against the shoulder. The bolt t' is then passed through the slot r in the plate R and secured by a nut, v. Upon the central portion, t, is placed a sleeve, w, which is passed through a slot, s, in the feed-bar S, and then clamped thereon by a nut, x, the sleeve being held on the stud by a nut, y.

At the upper end of the feed-bar S is secured a bolt, a, provided at its inner end with a roller, b, that works in a cam, c, cut in the periphery of the disk K. The lower end of the bar S is bent at right angles, and is provided with a teat or small projection, d. e is a small arm fulcrumed at f on the rear of the feed-bar S, and is provided with a slot, in which a chisel-pointed piece of metal, g, is secured by a set-screw, h. Against the upper part of the piece g the free end of a spring, j, 80 presses, as shown. The wire to be fed to the machine passes between the teat d and the piece g.

It will be seen that the stud T can be adjusted to any required position on the plate R, 95 thereby regulating the fulcrum of the feed-bar according as it is desired to feed the wire for a short or long nail, a reciprocating motion being imparted to the upper end of the feed-bar S by the cam c, and consequently an op- 100

posite motion is imparted to the lower end, which feeds the wire forward, the piece *g* being free to ride over the wire when the end of the feed-bar is moving backward; but when 5 moving forward the wire is gripped between the piece *g* and teat *d* and carried therewith.

Between the feed-bar and the knife I fix a tube, *X*, to guide the wire into the lower pointing-disk.

- 10 When it is desired to make very long nails, instead of attaching the teat *d*, piece *g*, and spring *j* directly onto the feed-bar *S*, I secure them to a slide, *U*, that works in a guide, *V*, (see Figs. 5 and 6,) secured to the frame of the 15 machine. The slide *U* is provided with a pin or stud, *k*, and the end of the feed-bar *S* is formed with a saddle to fit over same, as shown. The object of this arrangement is to feed the wire in a straight line, as with very long nails 20 the swing of the lower end of the feed-bar *S* would be so great as to raise the wire to an objectionable height above the cutting-off and pointing mechanism.

The operation is as follows: The wire being 25 pointed and in the position shown in Fig. 7 and the machine started, the cams *D* *D*² cause both the cutting-jaws *E* *E*² to descend until the knife *M* has cut off the wire, when the jaw *E* comes to a standstill, while the jaw *E*² continues to descend. The piece of wire that has 30 been cut off, being held between the knife *M* and the carrier *L*, is carried down to the gripping-jaws *C* *C*², to be headed in the usual manner. Just before the cut-off piece is delivered 35 to the gripping-jaws the die *N* comes into contact with the end of the wire and forms a point thereon. While the wire is held by the die *N* as it forms a point the feed-bar *S* is thrown

back ready to push the wire forward. The jaw *E*² now rises until the lower edge of the 40 knife is on a level with the bottom of the stay *Q*, when both the jaws *E* *E*² rise together until they are a short distance above the die *P*, when they both come to a standstill, and the feed-bar *S* is then operated to push the wire forward the required distance, when the jaws *E* 45 *E*² again descend and the operation is repeated.

What I claim as my invention is—

1. In combination with the cutting-jaws *E* *E*² of a tack or nail machine, the knife *M*, stay 50 *Q*, and pointing-dies *N* *P*, substantially as and for the purposes set forth.

2. The stud *T*, consisting of the central portion, *t*, ends *t* *t*², washer *u*, nut *v*, sleeve *w*, nut *x*, and nut *y*, in combination with the feed-bar 55 *S*, provided with a slot, *s*, and plate *R*, provided with a slot, *r*, substantially as and for the purposes set forth.

3. The slide *U*, provided with arm *e*, chisel-pointed piece *g*, spring *j*, teat *d*, and pin or 60 stud *k*, in combination with the guide *V* and feed-bar *S*, substantially as and for the purposes set forth.

4. The stay *Q*, knife *M*, and pointing-die *N*, secured to the cutting-jaws of a tack and nail 65 machine, in combination with a fixed pointing-die, *P*, and feed-bar *S*, constructed and operated substantially as and for the purposes set forth.

In testimony whereof I have signed my name 70 to this specification in the presence of two subscribing witnesses.

HORATIO CAMERON.
